UNITED STATES PATENT OFFICE.

HOMER L. BOYLE, OF GRAND RAPIDS, ASSIGNOR TO HIMSELF, AND LEON CHICHESTER, OF ALLEGAN, MICHIGAN,

THILL-CO尤LING.

SPECIFICATION forming part of Letters Patent No. 367,265, dated July 26, 1887.

Application filed March 28, 1887. Serial No. 232,796. (No model.)

To all whom it may concern:

Be it known that I, HOMER L. BOYLE, a citizen of the United States, residing at the city of Grand Rapids, in the county of Kent and 5 State of Michigan, have invented certain new and useful Improvements in Buggy-Clips, of which the following is a specification.

My invention relates to a detachable spring used in combination with a clip for buggies or 10 other vehicles, constructed as hereinafter described; and the objects of my invention are, first, to prevent the rattling of the thills or shafts; second, to form a ready means of attaching and detaching the thills from the 15 buggy; third, to provide an attachment which can be readily removed and which can be applied to the ordinary form of construction without alteration or change of the several parts; fourth, in connection with the objects 20 above referred to, to support or partially support the thills or shafts, taking the weight from the horse, and, if required, to support the outer ends of the thills a short distance from the ground. These objects I accomplish by 25 means of the mechanism illustrated in the accompanying drawings, in which—

Figure 1 is a side elevation of an ordinary buggy-clip and thill-iron to which my invention is applied. Fig. 2 is a side elevation of 30 the metallic spring detached from the buggy. Fig. 3 is a plan view of the blank which forms the spring before it has been bent up into the required form. Fig. 4 is a sectional view of the same on line XX of Fig. 1. Fig. 5 is a 35 plan view of the intermediate plate, which is placed between the spring and the thill-iron; and Fig. 6 is a side elevation of the spring, thill-iron, and connecting-bolt with the ear of the spring and clip-ear removed, in order to 40 show the position of the intermediate plate when in use.

A represents the front axle of the buggy.

C represents the clip, constructed in the ordinary manner and attached to the buggy- 45 axle.

S is a spring constructed in the form shown, and fitted between that part of the clip which surrounds the axle and the projecting ears which support the thill-iron. The lower front 50 part of the spring is bent upward, as shown by S', until it comes in contact with the thill-

iron T. The thill-iron fits between projecting ears E' E' of the clip, and is fastened by a bolt, I, which passes through such projecting ears, which ears do not differ from those in ordinary use, and therefore need no further description. The lower rear portion of the spring may be bent, as shown by B, in order to more securely hold the spring in place upon the clip. 55

E E represent ears of the spring, constructed 60 in the form shown in Fig. 3, and bent upon the dotted lines F F, so that when the spring is placed in the proper position upon the buggy-clip the ears E E fit over the ends of the bolt which holds the thill-iron to the clip A. The 65 bolt used does not project beyond the ears of the clip laterally, and the ears E E of the spring, fitting over the outer surface of the ears E' E', hold the bolt securely in place, so that such bolt cannot be removed without remov- 70 ing the spring S. The rear end of the spring S rests or presses against that portion of the clip which surrounds the axle, while the other or front end presses against the thill-iron which surrounds the connecting-bolt, automatically 75 taking up any wear that may occur either in the bolt or thill-iron, and thereby prevents any rattling of the parts.

F' F' are shoulders formed by the projection 80 of the spring, and these shoulders rest upon the surface of the ears, and the lower end of the spring, being bent around beneath the thill-iron, holds the spring securely in place.

I prefer to construct the spring out of sheet- 85 steel, as I have found this material well adapted to the purpose; but other substances may be used, and the form of the spring may be somewhat varied, without departing from the nature of my invention. In order to protect the spring S from wear, I design to use 90 an intermediate plate, D, Fig. 5, curved so as to fit upon the thill-iron and between it and the spring, as fully shown in Figs. 4 and 6. This plate is held by the spring S, so that it cannot move upon such spring, and thereby 95 prevents any wear upon such spring. I prefer to construct the plate D of metal; but other material may be used.

The part S' of the spring may be dispensed with in case it should not be desirable to support the thill by means of this spring; but I prefer to use the construction above described. 100

The spring, constructed as described, clasps the thill-iron beneath, holding the shoulders F' F' upon the projecting clip-ears E E', while the ears of the spring cover the outer surfaces 5 of the clip-ears, thus forming a double spring constructed of a single piece of metal, which can readily be attached and detached from the clip, and subserving the several purposes above named.

10 Having thus described my invention, what I claim to have invented, and desire to secure by Letters Patent, is—

15 1. An improved thill-coupling constructed of a single piece of spring-plate, having the lower end of its body portion bent forward and upward for extending beneath the thill and its sides extended forward for forming ears for embracing the ends of the connecting-bolt, substantially as described.

20 2. An improved thill-coupling constructed of a single piece of spring plate, having the lower end of its body portion bent forward and upward for extending beneath the thill and its sides extended forward for forming ears for 25 embracing the ends of the connecting-bolt, said ears having shoulders for resting upon the clip-lugs, substantially as set forth.

3. An improved thill-coupling constructed

of a single piece of spring-plate, having its upper end bent upward, rearward, and downward 30 for pressing against the clip-yoke, having, also, its lower end bent forward and upward for extending beneath the thill, and having its sides extended forward for forming ears for embracing the ends of the connecting-bolt, said ears having shoulders to rest upon the thill-lugs, substantially as described. 35

4. The combination of the thill-coupling constructed of a single piece of spring-plate bent upward, rearward, and downward at its 40 upper end, forward and upward at its lower end, and forward at its sides for forming shoudered ears, and a strip or separate piece located upon the front surface of the body portion of the coupling for receiving the wear, 45 substantially as specified.

5. The spring S, constructed as described, in combination with the buggy-clip, connecting-bolt, and thill-iron, said spring having its lower portion bent upward, so as to support 50 or partially support the weight of the thill, substantially as described.

HOMER L. BOYLE.
